UNITED STATES PATENT OFFICE.

RICHARD S. SEVERNS, OF DELANCO, NEW JERSEY.

COMPOSITION SHINGLE.

Application filed September 29, 1922. Serial No. 591,283.

To all whom it may concern:

Be it known that I, RICHARD S. SEVERNS, a citizen of the United States, residing at Delanco, in the county of Burlington and 5 State of New Jersey, have invented certain new and useful Improvements in Composition Shingles; and I hereby declare that the following is a full, clear, and exact description thereof, reference being had to the accompanying drawings, which form part of 10 this specification.

This invention relates to flexible prepared composition shingles for roofing. One object of the invention is to provide a twin 15 shingle provided with two triangular tabs extending transversely of the shingle, said tabs being adapted to give an appearance to the roof as though the same were covered by the usual single shingles, when said twin 20 shingles are laid in overlapping relation on said roof.

Another object of the invention is to provide a novel design for twin shingles which will afford a three-ply protection to the roof 25 at the tabs when said twin shingles are properly placed thereon.

A further object of the invention is to provide a twin shingle which by reason of the design thereof may be readily and 30 economically cut by machine from a strip of composition roofing material with a minimum of waste.

A still further object thereof is to provide 35 novel means for properly spacing the shingles while laying the same, and at the same time to provide means for fastening the outer and free ends of the exposed shingle tabs to the body portion of the shingle directly below said tab, in order to prevent 40 the outer ends of said tabs from curling upward under the action of the elements, whereby more complete protection is afforded.

I will explain the invention with reference 45 to the accompanying drawings which illustrate a practical embodiment thereof, to enable others to adopt and use the same; and summarize in the claims the novel features of the invention, and novel combinations of parts, for which protection is desired.

In the drawings:

Fig. 1 is a plan view of a portion of a roof covered with my novel twin shingles, 50 showing the arrangement of said shingles,

and the novel shingle spacing and tab fastening clip.

Fig. 2 is an enlarged detail plan view of one of my novel twin shingles.

Fig. 3 is an enlarged detail view of my 60 novel shingle spacing and tab fastening clip before bending same.

Fig. 4 is an enlarged section on the line 4—4 Fig. 1.

Fig. 5 is a diagrammatical plan view 65 showing how the novel shingles can be economically cut from a strip of flexible roofing material.

Fig. 6 is an enlarged section on the line 6—6 Fig. 1.

Fig. 7 is a top plan view of the parts shown in Fig. 6.

As shown in Fig. 2, each twin shingle comprises a rectangular body portion 1 of sufficient length to constitute two single 75 shingles, and of any suitable or desired width. On one edge of the body portion 1 and integral therewith, and located at distances equal to one-fourth and three-fourths respectively of the length of said body portion, are tabs 1^a, preferably triangular in shape, the side edges of said tabs sloping at an angle of 45° to the length of the body portion 1.

The length of each triangular tab 1^a is 85 preferably somewhat less than the width of the body portion 1, and the width of the base of each tab 1^a is preferably slightly less than one half the length of the body portion 1, the adjacent tabs being slightly separated at the edge of the body portion 1 intermediate the tabs 1^a, as shown at 1^c in Fig. 2, and the tabs being slightly spaced from the ends of the body 1 as shown at 1^{ex} in Fig. 2, the parts 1^{ex} of adjacent shingles 95 together equaling in length the part 1^c.

The apex of each triangular tab 1^a is preferably blunted as at 1^d, and in each tab, on the center line and adjacent the outer edge thereof, is a slot 1^e, as shown in Fig. 2, extending transversely to the axis of said tab, said slot 1^e being adapted to be engaged by the tongue of a shingle spacing and tab fastening clip 2, hereinafter described.

Intermediate the tabs 1^a in the edge 1^c of 105 body portion 1 is formed a slot 1^f of suitable depth and width to accommodate the tongue of said shingle spacing and tab fastening clip 2, and at the outer corners of the body portion 1, in the parts 1^{ex} thereof are 110

provided recesses 1^g, of the same depth as slot 1^f, but of only half the width thereof, so that when two shingles in the same row are placed end to end (as shown in Fig. 1) the adjacent recesses 1^g in the shingles will together form a slot similar in size to the grooves 1^f, and similar in location with respect to the adjacent tabs 1^a. Each slot formed by adjacent recesses 1^g, as above described, is also adapted to receive the tongue of a shingle spacing and tab fastening clip 2.

The shingle spacing and tab fastening clip 2, may be made of any desired metal, being preferably made from sheet copper and in form like a letter T, as shown in Fig. 3. Before using the clip the tongue or shank 2^b is bent upward at right angles to the portion 2^a, the portion 2^a thereof forming the base of said clip. The width of the tongue 2^b is preferably slightly less than the width of the slot 1^e and the slot 1^f. In use after a row of shingles is laid the base 2^a of the clip 2 is inserted under the edge 1^c of the lower row of shingles, as shown in Figs. 6 and 7, with tongue 2^b thereof extending upwardly through the slot 1^f (or 1^g, 1^g), said tongue 2^b is passed through the slot 1^e in the outer edge of the tab 1^a, superimposed thereon, and the projecting end of the tongue 2^b is then bent downward, as shown in Figs. 1, 4, 6 and 7, securely locking the clip 2 in position and effectively preventing the outer end of the superimposed tab 1^a from curling upwards, thereby ensuring a tight, durable and sightly roof covering.

As illustrated in Fig. 1, when the shingles are laid on the roof only the tabs 1^a and the part of the body portions 1 opposite and symmetrical with said tabs 1^a of each twin shingle are exposed to the weather, and the portions of the roof at the tabs are covered by three layers of the roofing material. Also since the shingles in adjacent rows are staggered the joints or abutting edges of adjacent shingles in the same row, will be covered by the tabs 1^a of the next row of shingles superimposed thereon, making said joints water-tight.

In laying the shingles a "starter" 3 shown in Fig. 1, (comprising a plain strip of the roofing material of the same width as the overall width of each twin shingle) is nailed along the lower edge of the roof. The lower row of shingles are then nailed end to end directly over said "starter" 3 with the blunt outer edges 1^d of the tabs 1^a flush with the outer and lower edge of said "starter". The "starter" 3 is provided for the purpose of filling the spaces between tabs in the lowest row of shingles. Clips 2 are then inserted in each slot 1^f (or 1^g, 1^g) of said middle ply of shingles, with the tongues 2^b thereof projecting through said slots. The shingles of the next upper row are then placed over the lower row with the joints thereof alternating

with the joints in the lower row as shown in Fig. 1, with the tab edges 1^a of the upper row coinciding with the body edges 1^c of the lower row of shingles, and the slots 1^e of the upper row registering with the slots 1^f (or 70 the slots formed by the adjacent recesses 1^g of abutting shingles) of the lower row. The tongues 2^b of clips 2 are passed through the slots 1^e of the tabs directly overlying same, and are then bent downward as shown in 75 Figs. 1, 4, 6 and 7, over the outer face of said tabs, holding the ends of the tabs 1^a down against the shingles directly below the same. The upper row of shingles may then be nailed down to the roof, and the above procedure repeated for subsequent rows of shingles.

By using the twin shingles only three nails are necessary for each twin shingle, whereas two nails are necessary for each single shingle, effecting a saving of one nail per twin shingle. The shingles may be effectively fastened in place by means of nails driven through perforations 1^p adjacent the recesses 1^g, in each outer corner of the twin 90 shingle and through perforations 1^s at the center of the twin shingles adjacent the slot 1^f, three nails being ample for each twin-shingle.

As indicated in Fig. 5, shingles of the 95 above design may be readily cut from strip roofing material with practically no loss of material, other than the small punchings made by cutting grooves 1^f and recesses 1^g, and about one fourth of a twin shingle, at 100 each end of the roofing strip, said losses being negligible. The shingles are uniform in size, and the completed roof has the appearance of being covered with square shingles having their vertical axes passing through 105 diametrically opposite corners thereof.

The shingles may be made of any desired strip roofing material, such as asphalt on a felt base, asbestos, or other suitable compositions, or if desired they may be made of 110 metal, wood, fibre, or the like, and when properly placed and spaced the shingles will form a three-ply thickness of roofing material on the roof at the tabs, and the outer ends of the tabs 1^a will be securely held down 115 by the clips 2 and cannot curl upwards.

What I claim is:

1. The combination of a shingle having a body portion with a plurality of integral spaced triangular tabs projecting from the 120 lower edge thereof, each tab having a perforation near its lower end, and the body portion having slots at each side of each tab, the slots in the body portion of one row of shingles being adapted to register 125 with the perforations in the tabs of the next superimposed row of shingles; with T-shaped metallic fastening clips having bases adapted to be inserted beneath the shingles in the middle ply with their shanks bent up- 130

ward and extending through the slots in such shingles, and also through the perforations in the tabs of the next superimposed row of shingles with their outer ends bent down 5 over the ends of said tabs to lock said tabs to the body portions of the underlying shingles; whereby the tabs of the upper ply of shingles are locked to the body portions of the middle ply and the imperforate lower 10 ply of shingles under said fastening clips preventing seepage of water past the clips and into the roof.

2. The combination of a shingle having a rectangular body portion approximately 15 equal in length to the width of two single shingles, and having triangular tabs integral with and extending from the lower edge of said body portion, the tabs being somewhat less in base length than half the length of 20 the edge of said body portion, the apex of each tab being blunted and having a perforation adjacent the outer edge thereof, and said body portion having a slot in its lower edge intermediate the tabs and having 25 recesses in its lower corners, the recesses in the ends of abutting shingles together form-

ing a slot like the slot intermediate the tabs, said shingles being adapted to be laid in overlapping rows with the perforations in the tabs of the upper row registering with 30 the slots in the body portions of the underlying shingles in the lower row, and said body portion being of such width as to give a 3-ply protection to the roof at the tabs when said shingles are laid in overlapping 35 rows; with T-shaped metallic fastening clips adapted to be inserted beneath the shingles in the middle ply with their shanks bent upward and extended through the slots in such shingles and also through the perforations 40 in the tabs of the outer ply of shingles and the outer ends of the shanks being bent down over the ends of said tabs to lock said tabs to the body portions of the underlying shingles; whereby the tabs of the upper ply are 45 locked to the body portions of the middle ply, the lower ply of shingles under the fastening clips preventing seepage of water past the clips and into the roof.

In testimony that I claim the foregoing 50 as my own, I affix my signature.

RICHARD S. SEVERNS.
